BY John Alledersheim ATTORNEY

UNITED STATES PATENT OFFICE.

HENRY C. WATT, OF PHILADELPHIA, PENNSYLVANIA.

ELECTRICAL CONDUCTOR.

SPECIFICATION forming part of Letters Patent No. 310,345, dated January 6, 1885.

Application filed March 26, 1884. (No model.)

To all whom it may concern:

Be it known that I, HENRY C. WATT, a citizen of the United States, residing in the city and county of Philadelphia, State of Pennsylvania, have invented a new and useful Improvement in Electric Conductors, which improvement is fully set forth in the following specification and accompanying drawings, in which—

10 Figure 1 is a side elevation of an electric conductor embodying my invention. Fig. 2 is a section enlarged in line *x x*.

Similar letters of reference indicate corresponding parts in the two figures.

15 My invention consists of an electric conductor which is thoroughly insulated and rendered water-proof, as will be hereinafter set forth.

Referring to the drawings, A represents 20 wires or electric conductors having a coating, *a*, of gum-turpentine, around which is a covering, *b*, of hemp or linen braid. The braid is coated with metallic or water-proof paint, as at *c*, around which is a covering, *d*, of hemp 25 or linen braid. A coating, *e*, of metallic or water-proof paint is applied to the covering *d*, and covered by braided wire *f*, and a coating, *g*, of tar applied to the wire.

It will be seen that the cable produced is 30 water-proof and the wires thoroughly insulated. The exterior wire, *f*, forms a flexible sheath, which protects the inner materials

from loosening and separating, and also prevents abrasion of said materials by the action of water and passing objects in the water. 35 The gum-turpentine around the wires A thoroughly insulates the same, and is a perfect non-conductor. It is impervious to the action of acids, moisture, rust, &c., and thoroughly waterproofs the wire or wires, said 40 gum being, it is believed, the exuding of turpentine-pine trees, or expressed from turpentine.

In lieu of gum-turpentine, I may use any equivalent resin. 45

Having thus described my invention, what I claim as new, and desire to secure by Letters Patent, is—

1. An electric conducting-wire having a coating of gum-turpentine, coverings of hemp 50 or linen braid, coatings of metallic or water-proof paint, and a covering of braided wire, substantially as and for the purpose set forth.

2. An electric conducting-wire having a coating of gum-turpentine, coverings of hemp 55 or linen braid, coatings of metallic or water-proof paint, a covering of braided wire, and an exterior of tar, substantially as and for the purpose set forth.

HENRY C. WATT.
